UNITED STATES PATENT OFFICE

JOSEPH KRAČMER, OF BRNO, CZECHOSLOVAKIA

DAM CONSTRUCTION

Application filed March 9, 1929. Serial No. 345,624.

My present invention relates generally to dams, and has particular reference to a dam construction provided with means for rendering the same watertight.

The dams to which my invention relates are formed of masonry blocks, masses of earth and the like, and in general, material which is not of itself perfectly watertight. A general object of the invention is to provide means for rendering such a dam construction watertight regardless of the pressure of the water on the upstream face of the dam.

A feature of my invention lies in accomplishing this object by means of suitably constructed and arranged walls which are arranged in spaced relationship to provide a series of watertight compartments, these compartments being filled in a predetermined manner with water of a predetermined height.

Another general object is to provide a construction wherein means are provided for permitting ready inspection of the dam, particularly of the interior thereof, whereby the same may be kept in constant repair and under constant control.

Other objects lie in providing improved means for sinking and mounting the base of the dam. In the case of a shallow rock foundation, it is a feature to provide means whereby leakage around the base may be promptly detected and may be remedied in a simple and novel manner. Where the rock foundation is of greater depth the foregoing feature is again resorted to and in addition thereto, it is a feature to mount the base in a pivotal or adjustable manner whereby the same may swing and thereby adjust itself under different circumstances.

Another object is to provide means for draining that portion of the dam construction which is exposed to the air.

For the attainment of the foregoing objects and such other objects as may herein-after appear or be pointed out, my invention consists of the construction and arrangement of parts as illustrated in the accompanying drawings, wherein—

Figure 1 is a diagrammatic elevational

cross-section of a dam construction embodying certain features of my invention;

Figure 2 is a view similar to Figure 1 showing the application of my invention to a dam of greater height;

Figure 3 is a view similar to Figures 1 and 2 showing the application of my invention to a dam of still greater height;

Figure 4 is a view similar to Figure 2 showing the watertight compartments arranged within the dam;

Figure 5 is a view similar to Figure 2 showing a modified arrangement of the watertight compartments;

Figure 6 is a view similar to Figure 2 showing my invention applied to a dam of some what different configuration;

Figure 7 is a cross-sectional view taken substantially along the line 7—7 of Figure 4;

Figure 8 is a cross-sectional view on an enlarged scale of the footing of a dam mounted in accordance with my invention in a shallow rock foundation;

Figure 9 is a view similar to Figure 8 showing the application of my invention to a deeper rock foundation;

Figures 10 and 11 are fragmentary horizontal cross-sectional views respectively of two different configurations of the walls forming the watertight compartments;

Figure 12 is a horizontal fragmentary cross-sectional view on an enlarged scale illustrating other features of my invention;

Figure 13 is a cross-sectional view taken substantially along the line 13—13 of Figure 7;

Figure 14 is a fragmentary cross-sectional view taken in the same direction as Figure 7 and illustrating a portion of the latter on an enlarged scale, this view being taken substantially along the line 14—14 of Figure 15;

Figure 15 is a cross-sectional view taken substantially along the line 15—15 of Figure 14;

Figure 16 is a cross-sectional plan view taken substantially along the line 16—16 of Figure 14.

The hollow watertight compartments of my present invention may be located either entirely on the upstream side of the dam,

entirely within the material of the dam, or partly on the upstream face and partly within the dam. The compartments are formed by a plurality of walls extending across the entire dam and arranged in spaced substantially parallel relationship. The space between each two adjacent walls constitutes a compartment within which a predetermined height of water may be provided for.

10 In accordance with my invention, the number of walls provided will vary, depending upon the height of water on the upstream side of the dam. Also, the heights of these spaced walls are successively less in the downstream direction, with the one exception that the second wall is of the same height as the first wall and at least equal to the height of the dam itself.

15 The differences in height depend upon the particular material of which the walls are constructed and the consequent watertightness of such material. In general, one height graduation is provided for every 10-25 meters of depth of the dammed water. Also, 20 it may be generally stated that if the number of height gradations is n , then the number of spaced walls is also equal to n , and the consequent number of hollow compartments formed will be $n-1$.

25 30 In Figure 1 I have shown a comparatively small dam designed to hold back a height of water between twenty and fifty meters. With such a relatively low height, two pressure gradations are sufficient. Accordingly, I have shown an outer wall A and a second or inner wall B, the latter being spaced from the wall A and being of substantially the same height as the latter. Within the space between the walls A and B I provide a height 35 of water approximately half of the total height of the dammed water. If the latter height is H , then the height of the water between the walls A and B is

$$40 \quad h = \frac{H}{2}.$$

45 The pressure diagram for the total water pressure on the wall A is represented by the triangle a, b, c , of height from b to c equal to H . Opposed to this pressure upon the wall A is a counter-pressure of the water within the watertight compartment, and the counter-pressure is represented by the pressure diagram e, f, c , the height f, c being equal to

$$50 \quad h = \frac{H}{2}.$$

55 By subtraction, the resultant water pressure against the wall A is represented by the figure a, e, f, b, d .

60 Similarly, the pressure from the upstream side upon the wall B is represented by the triangle e, f, c . Opposed to this is the counter-pressure of the entire dam construction

65 which is represented by the triangle t, u, v . The resultant pressure upon the wall B is represented by the figure t, y, z, u, x , the height of this last figure from u to z or from x to y being equal to h . It will be noted that 70 the resultant pressure against the walls A and B is in neither event higher than

$$75 \quad h = \frac{H}{2}.$$

80 Among the advantages which this construction attains is the fact that the leakage of water, if any, through the walls A and B is much less than it would be through a single wall of watertight material equal in thickness to the combined thickness of the walls A and B and the space between them. None of the walls, except the last downstream wall, has any pressures to support higher than a predetermined fraction of the total water pressure. In the case of Figure 1, the wall A need not be constructed to support any pressure greater than h . The wall which is furthest downstream has a much greater pressure to withstand, in no event higher than H and always somewhat less than H ; but on the other hand, this last or innermost wall is subject to hardly any penetration of water from the main body which is dammed.

85 90 In Figure 2, the pressure diagrams can be traced in a similar manner, this figure illustrating a dam of somewhat higher construction wherein three pressure gradations are arranged for. Thus, I have shown three spaced walls, instead of two, the walls of Figure 2 being designated by the reference letters A, B, C. The wall B is coextensive in height with the wall A, but the wall C is of less height. Accordingly, two hollow chambers are provided, Z_1 between the walls A, B, and Z_2 between the walls B, C. A height of water is provided in the space Z_1 equal to $2/3$ of the total height H , and a height of water is provided in the space Z_2 equal to h which is 95

100 105 $1/3 H$.

110 The pressure diagrams may be traced as before. Acting upon the outer wall A is a pressure represented by the triangle a, b, c , of height equal to H . Acting against the same wall from the inside is a pressure represented by the triangle e, f, c , of height equal to $2/3 H$. The resultant pressure upon the wall A is represented by the figure a, e, f, b , of height equal to

$$115 \quad h = \frac{H}{3}.$$

120 In a similar manner, it will be seen that the resultant pressure acting upon the wall B is diagrammatically represented by the figure g, l, m, i , this being the difference between the triangle g, j, i and the triangle l, j, m .

125 The pressure acting upon the rear wall C is represented by the figure t, u, z, y , this figure being a representation of the difference 130

between the triangle t, u, v (which is the counter-pressure of the dam itself) and the small triangle y, z, v , which is the pressure acting from the inside upon the wall C by virtue of the small height of water in the space Z_2 .

In Figure 3, a dam of still greater height is shown. In this case, four spaced walls are provided and designated A, B, C, D, thus producing three spaces Z_1, Z_2, Z_3 . The resultant pressure acting upon the wall A is represented by the figure a, e, f, b , of height equal to

$$15 \quad h = \frac{H}{4}.$$

The resultant pressure acting upon the wall B is represented by the figure g, l, m, i , of the same height

$$20 \quad h = \frac{H}{4}.$$

The resultant pressure acting upon the third wall C is represented by the figure n, r, s, o , also of height

$$25 \quad h = \frac{H}{4}.$$

The resultant pressure acting upon the last wall D is represented by the figure t, u, z, y .

In Figures 7-11, and also in Figure 9, I have shown the arrangement of walls and partitions within the spaces between the main walls hereinbefore referred to. A series of spaced vertical walls s' divide the spaces between the walls A, B, C, etc. into vertical shafts; and a series of horizontal spaced walls v' sub-divide these vertical shafts into chambers. Both the walls s' and v' are arranged in planes which are substantially perpendicular to the face of the dam, and in this way, the force of the dammed water is transmitted through the spaced walls A, B, C, etc. to the rear wall and to the dam construction proper.

45 A number of openings m'' are provided in certain of the walls s' so as to establish communication in a horizontal direction between the adjacent compartments. Similarly, suitable openings n' establish communication between the various stories. In this way, all the compartments of one space (such as the space Z_1 or the space Z_2) are in communication.

50 Openings o' are provided in all the walls s' at the base of the dam. The openings o' and m'' are of a sufficient size to permit the passage of a human being therethrough, and in this way, enable workmen or inspectors to examine the interior of the construction. 60 Such workmen or inspectors may also travel in a vertical direction by passing through the openings n' .

In Figure 11 a slight modification has been shown wherein the walls A and B are not absolutely plane, thereby making the com-

partments above-mentioned of substantially crescent or semicircular shape as shown in this figure. The wall C, or the last wall of the construction, may in certain cases be replaced by the dam construction itself or the upstream face of the valley wall. As mentioned before, this last wall is the only one which supports a pressure greater than a small fraction of the total pressure, but such last wall is subjected to no water action.

75 The resulting water pressure in all cases of upstream and inner walls is thus never greater than

$$h = \frac{H}{n},$$

80

where n is the number of stages or walls. The pressure upon the innermost wall is never greater than a value represented by the product of

$$H \text{ and } \frac{n-1}{n}.$$

85

I wish to point out that the front wall A always extends at least to the full height H of the dam, and that the second wall B is 90 always of the same height. Successively, the walls are then of less height. Thus, the third wall C is always of a height less than the height of the dam by an amount equal to

$$H.$$

95

I also wish to point out that the upper ends of the spaces Z_1, Z_2 , etc. are closed, and this construction, in conjunction with the wall 100 heights referred to, is of great importance from the standpoint of safety. Thus, if the wall A should fail or break, the water flowing into the space Z_1 will not pass any further than the wall B, the latter wall 105 thereby constituting something in the nature of a reserve or secondary barricade. The same is true if two walls A, B break, each successive wall serving to hold the water from flowing through the dam to a greater extent.

110 The chambers Z_2 and those following are provided with means for establishing communication with the atmosphere, this being accomplished by airshafts t' extending upwardly from the upper ends of successive 115 spaces through the preceding space. For example, in Figure 2, suitable airshafts are provided between the upper end of the space Z_2 and the atmosphere, these airshafts extending upwardly through the upper portion of the space Z_1 .

120 The reason why a plurality of airshafts is required, as shown in Figure 7, is that the entire construction previously described is made up of sections as shown in the last-mentioned figure. These sections are designated by the reference letters k_1-k_5 in Figure 7, and the continuity across the dam is established as shown in Figure 12 presently to be described.

125

130

The construction shown in Figure 6 will be clearly understandable from the foregoing description.

In Figures 4 and 5 I have shown a construction wherein the walls are partially or wholly within the body of the dam. The pressure diagrams in such cases are substantially like those shown in Figures 1-3, with the exception that the pressure is in each case increased by that of the portions of the dam body within which the walls are embedded.

The foregoing calculations are of course only theoretically correct and exist when the heights of water within the spaces are properly controlled and when the height of water in the basin is of the predetermined normal value H . By virtue of possible defects in the watertight walls, less favorable pressure conditions may sometimes exist. Thus, if the wall A were to break, the space Z_1 would fill up to the entire height H and the pressure conditions upon the next wall B would vary. Accordingly, it is preferable to construct the wall B to withstand a pressure condition which would be represented by the figure a, e', f', b , whose height is equal to

$$h = \frac{H}{2}.$$

In Figures 14, 15, and 16 I have shown the piping connections which are arranged at the base of the dam construction. These figures relate to a dam having two spaces Z_1, Z_2 as shown in Figure 8. In Figure 15, the left side is directed toward upstream, and the right side is directed toward the downstream side of the dam. Branching from two main conduits s^1 and s^2 are a pair of branch conduits z^1 and z^2 respectively. These conduits are used to fill the spaces Z_1 and Z_2 to the required levels. In addition to these conduits I provide the pipes e^1 and e^2 . The former extends from the upstream side into the space Z_1 and at the latter end it is provided with an automatic valve p^1 which opens only when the pressure in the space Z_1 is greater than that produced by a height of

$$\frac{H}{2}$$

or such other height as is contemplated. The piping e^2 establishes communication between the spaces Z_1 and Z_2 whenever the height of water in the latter space exceeds a predetermined amount. This pipe is also provided with the automatic safety valve p^2 .

To enable the watertight construction hereinbefore described to accommodate itself to variations, such as shrinkage of the dam body, I provide a mounting for the entire construction as illustrated in Figures 8 and 9. In the former figure, the base of the watertight construction is set into the foundation of rock in a wedge-like manner, and on both

sides an elastic asphaltic concrete (predominantly tar) is arranged as shown at k' and k'' . A pair of perforated pipes h' and h'' are embedded in the elastic concrete so that these pipes extend transversely across the entire width of the dam and on opposite sides of the watertight construction. A gallery K' extends transversely through the base of the watertight construction, and suitable branch pipes shown in dotted lines are made to extend from the perforated pipes h' and h'' into the gallery K' . If a settling of the watertight construction toward the right causes leakage at the left side of Figure 8, the elastic layer k'' will become compressed while the elastic layer k' will become loose, and in spite of its elasticity it may form cracks. The leakage of water into the layer k' will find its way into the pipe h' and thence into the gallery K' , whereby the leakage is detected. In such an event, hot air or steam is forced outwardly through the pipe branch shown in dotted lines, and in this way, the pipe h' is heated and in turn heats the elastic tar material around it. This softening of the latter, in conjunction with the pressure from above, causes the cracks to fill themselves and thereby to stop the leakage. In a similar manner, an inclination of the dam toward the left may cause leakage in the layer k'' , and in such an event, heating of the pipe h'' will remedy the defect.

The gallery K' is accessible from the chamber in which the piping and conduits, and their valves, are arranged, as seen in Figure 15.

Where the dam is mounted upon a very deep rock foundation as shown in Figure 9, a swinging of the dam, or inclination thereof in either direction, (due to shrinkage and the like) is made possible by means of a joint K mounted in a suitable socket within the rock foundation. The joint K is made of reinforced concrete and is similarly provided with the layers of elastic material k' and k'' . The advantages of the construction of Figure 8 are therefore carried forward into the construction of Figure 9.

The elasticity of the concrete, at its narrowest portion (between the lower ends of the layers k' and k'') allows for swinging and adjustment despite the fact that the construction is sunk into deep rock. The reinforcement rods take up the necessary stresses. A non-rusting plate j' is preferably provided on the water side, as seen in Figure 9 so as to prevent as much as possible a passage of water into the layer k' .

One of the features of my invention lies in providing for drainage of water which may find its way into the dam material on the downstream side. A layer of drainage material R' (Figure 4) or R (Figure 5) is arranged adjacent to the innermost wall of the watertight construction. At the base of

the construction, a transverse gallery Y'' is provided, and from this gallery a number of passages Y' establish communication with the layer R' (see Figures 8 and 9). Any 5 water which may have leaked through that part of the dam which is exposed to air, or which may have leaked even through the dam from the upstream side, is enabled to flow downwardly through the stone drainage layer 10 R' into the gallery Y'' , and this water is then led off into the main outlet as shown in Figures 15 and 16, thence in a downstream direction away from the dam.

In Figure 12 I have shown an improvement 15 relating to the sectional construction illustrated in Figure 7. The reason for the provision of sections is to enable expansion and contraction, and in Figure 12 an expansion joint is shown which consists of a smooth 20 plate G and by complementary plates E' and E'' . By the employment of two plates E' and G on the upstream side, the expansibility 25 of the joint is retained and an added protection is provided against the leakage of water from the basin through the expansion joint.

Having thus described my invention and illustrated its use, what I claim as new desire to secure by Letters Patent is—

1. In a dam construction, the combination 30 with a dam body composed of material penetrable by water, of a watertight construction which comprises a series of spaced substantially parallel walls extending across the entire width of the dam body, said walls including two upstream walls of substantially equal height, the other walls successively decreasing in height; said walls providing a set of watertight spaces adapted to be filled partially with water and partially with air 35 to permit rise of water level in a space without overflow into adjacent spaces, means for sealing said spaces at the tops thereof, and means for establishing communication between said spaces and the atmosphere.

45 2. In a dam construction, the combination with a dam body composed of material penetrable by water, of a watertight construction which comprises a series of spaced substantially parallel walls extending across the entire width of the dam body, said walls including two upstream walls of substantially equal height, the other walls successively decreasing in height; said walls providing a set of watertight spaces adapted to receive water at pre- 50 determined levels, means for sealing said spaces at the tops thereof, and means for establishing communication between said spaces and the atmosphere; said last-named means comprising an air duct leading from 55 the top of each space upwardly through the upper portion of the preceding space.

3. In a dam construction, the combination 60 with a dam body of material penetrable by water, of a watertight construction composed of a set of spaced parallel walls extending

across the width of the dam body, a gallery extending across the dam through the base thereof, a layer of elastic normally solid softenable material on each side of the watertight construction at the base of the latter, and means for softening said layers through 70 said gallery.

4. In a dam construction, the combination 75 with a dam body of material penetrable by water, of a watertight construction composed of a set of spaced parallel walls extending across the width of the dam body, a gallery extending across the dam through the base thereof, a layer of elastic normally solid softenable material on each side of the watertight construction at the base of the latter, and means for softening said layers through 80 said gallery, said last-named means comprising a perforated pipe embedded in said elastic material, and a conduit extending from 85 said gallery to said perforated pipe.

5. In a dam construction, the combination 90 with a dam body of material penetrable by water, of a watertight construction consisting of a set of spaced parallel walls extending across the width of the dam body, and an adjustable base for said construction, said base comprising a downwardly extending concrete joint, said joint being provided with downwardly converging recesses defining a relatively narrow and elastic portion between them.

6. In a dam construction, the combination 95 with a dam body of material penetrable by water, of a watertight construction consisting of a set of spaced parallel walls extending across the width of the dam body, and an adjustable base for said construction, said base comprising a downwardly extending concrete joint, said joint being provided with downwardly converging recesses defining a relatively narrow and elastic portion between them, and an elastic normally hard yet softenable material within said recesses.

7. In a dam construction, the combination 100 with a dam body of material penetrable by water, of a watertight construction consisting of a set of spaced parallel walls extending across the width of the dam body, and an adjustable base for said construction, said base comprising a downwardly extending concrete joint, said joint being provided with downwardly converging recesses defining a relatively narrow and elastic portion between them, an elastic normally hard yet softenable 105 material within said recesses, and means for softening said last-mentioned material.

8. In a dam construction, the combination 110 with a dam body composed of material penetrable by water, of a watertight construction which comprises a series of spaced substantially parallel walls extending across the entire width of the dam body, said watertight construction comprising a set of adjacent sections separated by vertical spaces, 115 120 125 130

and an expansion joint in each of said spaces, said joint consisting of two superposed U-shaped watertight plates, on the water side of the vertical space and a single U-shaped plate on the air side of the vertical space, said three U-shaped plates having their sides connected to the edges of the adjacent divisions of the watertight construction.

In testimony whereof I affix my signature.
